RAZOR WITH MEANS FOR RECONDITIONING
THE CUTTING EDGES OF RAZOR BLADES

Zemach Auerbach, Bronx, N. Y.

Application February 14, 1947, Serial No. 728,572

2 Claims. (Cl. 30—36)

1

This invention relates to means for reconditioning the cutting edges of razor blades.

Broadly, it is an object of my invention to provide a means for reconditioning the cutting edges of razor blades in combination or in association with a safety razor.

More particularly, it is an object of my invention to provide a movable plate between the blade and the cap of a razor so that by moving the plate laterally, the edges of the plate will realign the irregularities of the cutting edges.

During the shaving process, the hairs bend parts of the fine cutting edge outward so that the cutting edge loses its keenness. Various means have been employed to sharpen the cutting edges, such as honing on a flat or arcuate stone, stropping, etc. I have found that by moving a straight edge over the cutting edges of the blade that the irregularities of the cutting edges created in shaving become easily straightened thus realigning the cutting edges and prolonging the shaving life of the blade.

A further object is to provide a combination cap and reconditioning means for a safety razor blade.

For a fuller understanding of the nature and objects of the invention, reference is had to the following detailed description, in connection with the accompanying drawing, in which:

Figure 1 is a top view of a safety razor with part of the cap and part of the plate for realigning the cutting edges broken away, the realigning plate being shown in shaving position.

Figure 2 is a side view thereof, part of the handle being broken away.

Figure 3 is an enlarged side view, partly in section, showing the realigning plate moved over one cutting edge, the opposite cutting edge being shown partly bent upward after use.

Figure 4 is a view taken along line 4—4 of Figure 3 showing the one cutting edge having been realigned while the opposite cutting edge shows the irregularities after shaving, part of the realigning plate being shown partly broken away.

Figure 5 is a greatly enlarged view of one corner of the realigning plate and razor blade showing the edge of the plate over the cutting edge of the blade, the corner of the plate having been broken away to show the irregularities of the cutting edge of the blade after shaving.

Figure 6 is a top view of a modified form of the invention comprising a combination cap and slideable member for realigning the cutting edges of a blade in shaving position, parts shown broken away.

2

Figure 7 is the same view as Figure 6 except that the parts are shown in position for realigning the irregularities of the cutting edges of the blade.

5 Figure 8 is a section taken through line 8—8 of Figure 7.

Referring to the drawing, numeral 10 represents a cap having a concave inner surface 11 with a central projecting screw 12 well known in the razor art. An arcuate plate 13 of the same arc as the concave inner surface 11 is positioned beneath the cap 10. Plate 13 has a central opening 14 and other openings 15 and a pair of opposed projections or flanges 16; the space 15 between flanges 16 being slightly wider than the length of the cap 10. The edges 17 of cap 10 act as guides for plate 13. The inner surfaces of the flanges 16 slide against edges 17 of the cap 10 when the plate 13 is manually moved laterally. 20 Central screw 12 passes through opening 14 and the openings 15 permit any depending parts, such as lugs (not shown) to pass through openings 15. The edges 18 and 19 act as stops against screw 12 to limit the lateral movement of plate 13. The edges of openings 15 may be used for the same purpose, that is to act as stops against any projections from the bottom of the cap. The longitudinal edges 20 of plate 13 are rounded and are permitted to slide over the cutting edges 21 and 22 of the blade 23, since the size of opening 14 is large enough to permit edges 20 to pass over cutting edges 21 and 22.

25 A flexible razor blade 23 is placed between the plate 13 and the platform 24 as is well known in the art. Handle 25 is screwed onto screw 12 drawing the cap downward, flexing blade 23 and tightening the plate 13 and blade 23 between the cap 10 and platform 24, preventing movement of the blade and plate 13.

30 35 In order to use the plate 13 for reconditioning the cutting edges of the blade 23, the handle 25 is turned so that the cap 10 is loosened sufficiently to permit the plate 13 to be moved laterally by the thumb and one finger pressing upon the opposed flanges 16. The edges 20 of plate 13 ride over the cutting edges 21 and 22 of the blade thus straightening the irregularities created in the cutting edges by shaving.

35 40 When the plate 13 is in the center of the razor as shown in Figures 1 and 2, and the handle 25 tightened, the razor is in condition for shaving.

Referring to Figures 6, 7, and 8 which show a modification of the device shown in Figures 1 to 5 inclusive, numeral 26 is a movable plate with an arcuate inner surface 27 and having a rectangular opening 28 and a pair of opposed notches 29

communicating with opening 28. Projecting into opening 28 at each end are opposed pins or lugs 30. A bar 31 is centrally disposed within the rectangular opening 28 running parallel thereto. At each end of the bar 31 there is a notch 32 within which the pin 30 rides. A depending screw (not shown) projects from the center of the bar 31 and is adapted to pass through a central opening in the platform 33. A handle similar to 25 is adapted to screw onto the depending screw in order to tighten the bar 31. A pin 34 projects from the center of the bar 31. A slideable locking member 35 having an opening 36 into which pin 34 passes and having depending projections 39 is adapted to slide longitudinally upon bar 31. Lugs 37 projecting from the lower portion of bar 31 are adapted to fit within channel 38 of platform 33.

In order to use the device shown in Figures 6 to 8 inclusive, a double-edged blade is placed upon the arcuate platform 33 and the central screw depending from the movable bar 31 passed through the well known channel of the blade 23. The handle is then screwed onto the depending screw so that the blade 23 is flexed. The position of the locking member 35 and the plate 26 is that shown in Figure 6. The locking member 35 is moved to the right so that pin 34 is at the left of opening 36. The razor is now in position for shaving.

In order to realign the irregularities created by shaving of the cutting edges 21 and 22 of the blade, the handle of the razor is loosened slightly and the slideable locking member moved to the left as shown in Figure 7 so that the depending projections 39 are aligned with the opposed notches 29. The edges 40—40 of the movable plate 26 are then grasped between the fingers and moved laterally from side to side so that the longitudinal edges 41 ride over the cutting edges 21 and 22 of the blade thus straightening the irregularities of the cutting edges due to shaving. During the lateral movement of plate 26 pins 30 move within the notches 32 of the bar 31 and projections 39 enter the notches 29. In order to again lock the razor in shaving position, plate 26 is moved centrally over platform 33, the locking member 35 is moved to the right as shown in Figure 6 and the handle is then tightened.

It is obvious that various changes and modifications may be made in the details of construction and arrangement of parts without departing from the general spirit of the invention.

5 I claim:

1. A safety razor for a double edged blade having cutting edges, a movable plate having edges adapted to ride over said cutting edges of said blade, a rectangular opening in said movable plate and opposed notches communicating with said opening, a bar within said opening, opposed pins projecting into the ends of said rectangular opening, notches at the ends of said bar to slideably receive said pins, a screw depending from said bar, a pin projecting from the top of said bar, a locking member with depending projections movable along said bar guided by said pin, a platform for said blade, and a handle for said razor, said handle having a threaded opening adapted to receive said screw for tightening said platform with said bar and plate.

2. A safety razor for a double edged blade having cutting edges, a movable plate having edges adapted to ride over said cutting edges of said blade, a rectangular opening in said movable plate and opposed notches communicating with said opening, a platform for supporting said blade, a bar within said opening, opposed pins projecting into the ends of said opening, notches at the ends of said bar to slideably receive said pins, a screw depending from said bar, a pin projecting from the top of said bar, a locking member with depending projections movable along said bar and guided by said pin, a handle for said razor adapted to coat with said depending screw for tightening said platform with said bar and said plate.

ZEMACH AUERBACH.
